UNITED STATES PATENT OFFICE.

FITZHUGH L. BECK, OF BARKSDALE, TEXAS.

PNEUMATICALLY-OPERATED RAILWAY GATE.

Application filed September 9, 1926. Serial No. 134,435.

The present invention relates to pneumatically operated railway gates having for an object the provision of mechanism, movement of which is initiated by the train, when it approaches a highway, to permit the gates to be gradually lowered across the highway into an obstructing position on both sides of the railway.

Another object of the invention is to provide gate operating mechanism for railroads which include train carried means which is adjustable for operative contact with track mechanism on either side of the track to insure lowering of the gates immaterial of whether the train is moving forward or backward.

A further object of the invention is to provide pneumatically operated gates for railroads which gradually close as the train approaches the highway, the mechanism including movable means which functions immaterial of whether the train is moving forward or backward, the air pressure being relieved as soon as the train reaches the highway to permit the gates to be mechanically actuated into an open position.

Other objects of the invention will be apparent from the following description of the present preferred form of the invention taken in connection with the accompanying drawings, wherein:

Fig. 1 is a top plan view of pneumatically operated gates constructed in accordance with the present invention illustrating their application.

Fig. 2 is a plan view of the locomotive carried means of the present invention illustrating its application.

Fig. 3 is an elevational view of gates constructed in accordance with the present invention illustrating their application.

Fig. 4 is a vertical sectional view of one of the gate elements and associate mechanism.

Fig. 5 is a perspective view of the locomotive carried means, and

Fig. 6 is a vertical sectional view of one of the pumps illustrating the manner in which it is operated by the locomotive carried means.

In order to illustrate the application of this invention a railway generally designated 7 is shown, which embodies tracks 8 of standard construction, and is intersected by a highway 9. Although only a single track is illustrated in the drawing it is of course

to be understood that the same mechanism is applicable to all tracks intersected by the highway.

The gates are mounted in the customary manner on both sides of the railway and each gate consists of a pair of elements one located on each side of the highway and each consisting of a base 10 which has a cylindrical housing 11 issuing from its upper face. A standard or tower 12 extends from the upper terminal of the housing 11 and extends for an appreciable distance thereabove terminating in a bifurcated upper end which receives a pulley wheel 13. Mounted within the housing 11 and formed integral with the base thereof is a cylinder 14 which extends upwardly in the housing to a point approximately midway the ends of the latter the upper end thereof being closed except for a slot 15 which is formed therein. Reciprocally mounted in the cylinder 14 is a piston 16 which is equipped with a wrist pin 17 the latter being engaged by one end of a piston rod 18. The opposite end of said rod extends through the slot 15 and is revolvably engaged, as indicated at 19, with one end of a link 20. The opposite end of the link is secured to a shaft 21 carried by the top of the housing 11, the shaft having also secured thereto one end of a gate element 22. The outer end of the gate element is engaged by one end of a cable 23 the intermediate portion of the latter being trained around the pulley 13 while the opposite end is engaged by a weight 24. Communicating with the cylinder 14 through the base 10 is an air inlet pipe 25 and an air outlet pipe 26. The air inlet pipe is provided with a one-way valve to permit ingress of air into the cylinder 14 and preventing egress of air from the cylinder through this pipe. Conversely, the outlet pipe 26 is provided with a one-way valve which permits the egress of air from the cylinder and prevents ingress of air thereto through the outlet pipe. The inlet pipe 25 leads to and is in communication with pumps, in a manner hereinafter described, while the outlet pipe 26 extends to a point in close proximity to one of the rails 8 and terminates in a valve 27 which is adapted to be impinged by the flanges of the train wheels in order to open the valves and permit air to be discharged from the cylinder 14.

Arranged on each side of the highway 9 is a series of air conduits or pipes, the series

on one side being designated 28, 29, 30, and 31, while the series on the other side is designated 28', 29', 30', and 31'. Each of the conduits on both sides of the highway is 5 equipped with five pumps 32 which are identical in construction. As illustrated to advantage in Fig. 6 each pump consists of a cylinder 33 which has a piston 34 reciprocally mounted therein and equipped with a 10 piston rod 35 which operates through one end of the cylinder and terminates in a roller 36. The opposite end of the cylinder 33 is closed except for a pair of openings which receive nipples 37 and 38. The nipple 37 is in communication with one of the conduit pipes such as the pipe 28 illustrated in Fig. 6, while the other nipple 38 is adapted to be placed in communication with a 15 source of air supply in a manner well known in the art. Each of the nipples is provided with a valve 39 so as to permit the air to flow in only one direction therethrough. For instance, the air can flow only into the cylinder through the nipple 38 and can flow 20 only from the cylinder through the nipple 37. As illustrated to advantage in Fig. 1 the conduits 28 and 29 extend only to the cylinders 14 on one side of the railway while the conduits 30 and 31 extend only to the 25 cylinders on the opposite sides of the railway. Correspondingly the conduits 28' and 29' are in circuit with the conduits 28 and 29 while the conduits 30' and 31' are in circuit with the conduits 30 and 31. Each of 30 the conduits is provided with a one-way valve 39 through which the air is permitted to pass in the direction indicated by the arrows in the drawings. Manifestly, therefore, as the pistons 34 are forced downwardly in their cylinders the air in the cylinders is forced through the conduits into the cylinders 14 through the pipes 25, thereby 35 elevating the piston 16 and permitting the gate elements to be lowered into an obstructing position across the highway 9 in an apparent manner.

In order to urge the pistons 34 downwardly in the cylinders 33 suitable locomotive carried means is provided generally 50 designated 40. This means in the present instance consists of a substantially V shape plate or abutment the opposite ends of which have portions 41 extended therefrom and curled about rods 42 which extend transversely across a locomotive 43. The abutment is sufficiently wide to extend completely across four conduits so as to simultaneously impinge against rollers 36 of one 55 set of pumps. In the present instance five sets of pumps are in communication with each series of conduits and the sets are spaced a predetermined distance which in actual use is about 120 feet apart. When the abutment strikes the first set of pumps 60 the pistons 16 receive the first impact and as

the locomotive progresses along the track the abutment will successively engage each set of pumps until the five pumps have been actuated at which time the gate elements will have been completely lowered. When 70 the train reaches the highway the air will be released from the cylinders 14 in a manner above described thereby permitting the gate elements 22 to be automatically elevated by the weights 24. When the train is to be 75 backed across the highway it is only necessary to slide the abutment 40 on the bars 42 to the opposite side of the locomotive and this may be done through the medium of a lever 44 which is pivotally mounted on the locomotive and if desired may be actuated from the cab. The operation of the pumps in order to urge the gate elements into a closed or obstructing position is identical. The gates are closed and are permitted to be 80 opened in the same identical manner immaterial of whether the train is moving in a forward direction over the highway or backing thereover, it being only necessary that the abutment 40 be shifted from one side to 85 the other in the manner already described.

The pistons 34 are positively and automatically elevated by springs 35', one of which encircles each of the piston rods 35. The lower end of each spring impinges 90 against the top of the cylinder while the upper end of the spring is anchored on the piston rod. In this way the rollers 36 are maintained at the desired height to be engaged by the abutment 40. The shape of the abutment 40 is likewise important since it permits the abutment to wipe over the rollers 36 without entailing a sharp impact besides permitting the abutment to function when the locomotive moves in either direction. Furthermore, by providing a plurality of sets of pumps all of the gate elements are simultaneously but gradually lowered. 100

It is of course to be understood that various changes may be made in the invention within the scope of the claims hereto appended. 110

What I claim is:—

1. A railway gate operating mechanism including gates mounted on both sides of the railroad, a series of air conduits and pumps carried thereby, arranged near each track on opposite sides of the highway, a locomotive carried means cooperable with said pumps to close the gates, said means being adjustable for coaction with the pumps of either series of conduits. 115

2. A railway gate operating mechanism for highways including gates mounted on both sides of the railway, means to move the gates into a closed position across the highway embodying air conduits and pumps carried thereby in circuit with said gates, locomotive carried means to open said con- 120 125 130

duits and permit closing of the gates, and means for coaction with the pumps arranged near the tracks across the highway to be impinged by the locomotive wheels for releasing the conduits and permitting the opening of the gates.

3. In combination with a railroad intersected by a highway, gates mounted on opposite sides of the railroad and operable into closed position across the highway, means for closing said gates including mechanism mounted along the railroad on each side of the highway and in operative communication with said gates, and a train carried abutment arranged on one side of the train to engage the mechanism on one side of the highway for closing the gates when the train is moving in a forward direction, said abutment being movable to the opposite side of the train for engagement with the mechanism on the opposite side of the highway to close the gates when the train is moving backwards.

4. In combination with a railroad intersected by a highway, gates mounted on opposite sides of the railroad adapted to be closed across the highway, a series of pumps arranged along the railroad on opposite sides of the highway and on opposite sides of the railroad, said pumps being in opera-

tive communication with the gates, train carried means engageable with the series of pumps on one side of the highway to close the gates when the train is moving in a forward direction, said means being adjustable for engagement with said pumps to cause closing of the gates when the train moves backwards over the highway, and train engaging means arranged along the track near the highway to release said gates when the train moves over the highway.

5. In combination with a railroad intersected by a highway, gates mounted on opposite sides of the railroad and on opposite side of the highway, means mounted along the railroad on each side of the highway and in operative connection with the gates, and locomotive carried means arranged on one side of the locomotive to coact with the means on one side of the highway when the locomotive is moving forward, said locomotive carried means being movable to the other side for engagement with the means on the opposite side of the highway when the locomotive moves backward, coaction of the first said means and locomotive carried means causing the gates to be closed.

In testimony whereof I affix my signature.

FITZHUGH L. BECK.
